CLAIM

The ornamental design for a dental implant fixture, as shown and described.

DESCRIPTION

FIG. 1 is a front elevational view of a dental implant fixture, showing my design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged cross-sectional view thereof taken along line A—A of FIG. 4;

FIG. 8 is a cross-sectional view thereof taken along line B—B in FIG. 4;

FIG. 9 is a cross-sectional view thereof taken along line C—C in FIG. 1;

FIG. 10 is a cross-sectional view taken along line D—D in FIG. 1; and,

FIG. 11 is a top and front view thereof.

The broken lines shown in the figure drawings are for illustrative purposes only and form no part of the claimed design.
